(57) **CLAIM**

The ornamental design for an air cooled motor, as shown and described.

DESCRIPTION

FIG. 1 is a back view of the air cooled motor according to the invention.

FIG. 2 is a bottom view of the air cooled motor according to the invention.

FIG. 3 is a front view of the air cooled motor according to the invention.

FIG. 4 is a left side view of the air cooled motor according to the invention.

FIG. 5 is a perspective view of the air cooled motor according to the invention.

FIG. 6 is a second perspective view of the air cooled motor according to the invention.

FIG. 7 is a right side view of the air cooled motor according to the invention; and,

FIG. 8 is a top view of the air cooled motor according to the invention.

The broken lines in the drawings depict portions of the air cooled motor and form no part of the claimed design.
